FIG. 2.

INVENTOR
John Scobie

BY

Emmett B. Wiser
ATTORNEY

UNITED STATES PATENT OFFICE

91,970

DESIGN FOR A COMBINATION BED LAMP, NIGHT TABLE, AND STORAGE CABINET

John Scobie, Detroit, Mich.

Application January 6, 1934, Serial No. 50,343

Term of patent 3½ years

To all whom it may concern:

Be it known that I, JOHN SCOBIE, a citizen of the United States, residing at Detroit, in the county of Wayne and State of Michigan, have invented a new, original, and ornamental Design for a Combination Bed Lamp, Night Table and Storage Cabinet, of which the following is a specification, reference being had to the accompanying drawing, forming part thereof.

Fig. 1 is a side perspective view of a combination bed lamp, night table and storage cabinet showing my new design.

Fig. 2 is a front perspective view thereof.

I claim:

The ornamental design for a combination bed lamp, night table, and storage cabinet, as shown.

JOHN SCOBIE.
